US0D1004033S

(12) **United States Design Patent** (10) Patent No.: **US D1,004,033 S**
(45) Date of Patent: ** Nov. 7, 2023

(54) **HANDGUARD FOR A GUN**

(71) Applicant: **Sagi Faifer**, Mishmar Hashiva (IL)

(72) Inventor: **Sagi Faifer**, Mishmar Hashiva (IL)

(**) Term: **15 Years**

(21) Appl. No.: **29/721,357**

(22) Filed: **Jan. 20, 2020**

(51) LOC (14) Cl. **22-01**

(52) U.S. Cl.

USPC **D22/108**

(58) **Field of Classification Search**

USPC D22/108; D21/571-575

CPC F41C 23/10; F41C 23/14; F41C 23/16;

F41C 23/18

CLAIM

The ornamental design for a handguard for a gun, as shown and described.

DESCRIPTION

FIG. 1 is a top, front, right perspective view of a handguard for a gun in accordance with my new design;
 FIG. 2 is a top, front, right side perspective view of the handguard for a gun of FIG. 1;
 FIG. 3 is a top, rear, left perspective view of the handguard for a gun of FIG. 1;

FIG. 4 is a left side view of the handguard for a gun of FIG. 1;
FIG. 5 is a right side view of the handguard for a gun of FIG. 1;
FIG. 6 is a top view of the handguard for a gun of FIG. 1;
FIG. 7 is a bottom view of the handguard for a gun of FIG. 1;
FIG. 8 is a front view of the handguard for a gun of FIG. 1;
FIG. 9 is a rear view of the handguard for a gun of FIG. 1;
FIG. 10 is a bottom, rear, right side perspective view of the handguard for a gun of FIG. 1;
FIG. 11 is a bottom, front, left side perspective view of the handguard for a gun of FIG. 1;
FIG. 12 is a front, top, right side perspective view of the handguard for a gun of FIG. 1;
FIG. 13 is a rear, top, left side perspective view of the handguard for a gun of FIG. 1;
FIG. 14 is a vertical cross-section of the handguard for a gun of FIG. 8, along line 14-14;
FIG. 15 is a vertical cross-section of the handguard for a gun of FIG. 14, along line 15-15;

FIG. 16 is a vertical cross-section of the handguard for a gun of FIG. 14, along line 16-16;
FIG. 17 is a vertical cross-section of the handguard for a gun of FIG. 14, along line 17-17;
FIG. 18 is a vertical cross-section of the handguard for a gun of FIG. 14, along line 18-18;
FIG. 19 is a vertical cross-section of the handguard for a gun of FIG. 14, along line 19-19;
FIG. 20 is a vertical cross-section of the handguard for a gun of FIG. 14, along line 20-20;
FIG. 21 is a vertical cross-section of the handguard for a gun of FIG. 14, along line 21-21; and,
FIG. 22 is a vertical cross-section of the handguard for a gun of FIG. 14, along line 22-22.
The broken lines immediately adjacent the shaded areas represent the bounds of the claimed design. All broken lines are directed to environment and are for illustrative purposes only and form no part of the claimed design.
